UNITED STATES PATENT OFFICE.

ALBERT W. MORSE, OF NEW YORK, N. Y.

METHOD AND APPARATUS FOR HEATING OIL.

Application filed June 13, 1927. Serial No. 198,555.

This invention relates to methods and apparatuses for heating oil.

It is the particular object of the invention to provide simple and efficient means to raise 5 the temperature of fuel oil supplied to the burner of an oil fired furnace to such a degree that it can be burned satisfactorily.

Another object is to accomplish this result with a compact structure which is imbedded 10 in the furnace.

A further object is to provide means in the heater structure permitting of ready renewal of those parts which are subjected to intense heat without the necessity of interrupting the 15 flow of oil to the burner.

A still further object is to automatically regulate the rate of flow of oil within the heater structure according to its temperature in order to obtain a uniform temperature of 20 oil at the discharge end of the heater.

Still further objects will become apparent in the following specification in which a preferred embodiment of my invention is described. The invention is illustrated by the 25 accompanying drawings in which

Fig. 1 is a fragmentary elevational view of the front of a furnace equipped for the use of oil as fuel;

Fig. 2 is a horizontal sectional view along 30 the plane of line 2—2 in Fig. 1;

Fig. 3 is a vertical cross sectional view along the plane of line 3—3 in Fig. 2; and

Fig. 4 is a fragmentary vertical sectional view along the plane of line 4—4 in Fig. 2.

Like characters of reference denote similar 35 parts throughout the several views and the following specification.

The entire heater and burner parts are shown diagrammatically in exterior views 40 only, being well known in the art.

10 is a furnace having a front wall 11 and side walls 12 and a floor 13, usually of fire bricks, defining a combustion chamber or firebox 14.

15 is an oil supply pipe connected to an oil pump (not shown) which forces oil into this pipe from an oil tank (not shown). 16 and 16^a are tubes projecting into the furnace and joined together at their inner ends by a return bend 17. These tubes are connected to the oil supply pipe 15 by elbows 18 and 18^a forming a long U-shaped loop 19 in the oil pipe. 20 and 20^a are union connections in the oil line 15 at both sides of the loop 19. 21 and 21^a are cut-out valves in the oil pipe 15 near each of the union connections 20 and 20^a.

22 and 22^a are T connections near, respectively, the outlet side of cut-out valve 21 and the inlet side of cut-out valve 21^a. The oil supply pipe 15 is continued at substantially right angles at T 22 to a similar T 23 and through the same to a burner 24. 25 is a by-pass pipe connecting T 23 with T 22^a by means of an elbow connection 26. 27 is a by-pass valve interposed between T 23 and elbow 26. 28 is a union connection and 29 an automatic stop and check valve in the oil supply pipe 15 at the inlet end of the T 22^a, and 30 is a union connection in the oil line 15 at the outlet end of T 23.

The burner 24 is rigged up in front of the furnace 10 in alignment with a combustion block 31 through which the combustible mixture from the burner is discharged into the combustion chamber 14.

32 is a return pipe for the surplus oil from the burner to the tank. In the oil return pipe 32 is placed a thermostatic control valve 33. 34 is a flexible connection from the thermostatic valve 33 to an expansible element 35 inserted into the oil supply pipe 15 at T 22. The thermostatic valve 33 is of a kind in which a valve member is reciprocated by an expansible element such as 35 which transmits its motion by the flexible connection 34 to the valve member and opens the valve when expanded and permits it to close when contracted. Closely adjacent to thermostatic valve 33, T_s 36 and 36^a are placed in the oil return line 32 and connected by suitable elbows 37 and 37^a to a by-pass pipe 38 equipped with a by-pass valve 39.

The inwardly projecting loop 19 of the oil supply pipe 15 is encased with fire bricks 40 forming a chamber 41. One wall of the chamber 41, preferably the top wall, is provided with a series of openings 42.

The operation of my device is as follows:

Oil is pumped from the oil tank into the oil supply pipe 15 under full line pressure 100 and passes through the automatic stop and check valve 29, through valve 21^a into tubes 16 and 16^a, and thence through valve 21 and T_s 22 and 23 into the burner 24 which is adjusted to discharge the desired quantity of oil admixed with air or steam through block 31 into the combustion chamber 14 where ignition takes place in the manner well known in the art. The surplus oil is returned to the oil tank by way of the oil return pipe 32 through thermostatic valve 33. The oil, 110 while passing through the loop 19 in the oil

supply pipe 15, is subjected to a high degree of heat from the fire in the combustion chamber 14 and the radiant heat from the fire-bricks surrounding it. It is obvious that by varying the openings 42 and the size of the chamber 41, as well as the length of the loop 19, the degree of heat imparted to the oil may be governed to a certain extent to suit various local conditions. The principal purpose of this invention, however, is to so control the temperature of the oil that the same will be uniform at the burner. As soon as the desired temperature is reached, the expansible element 35 in direct line of oil travel after the oil leaves the loop 19 expands to such a degree that it opens the thermostatic control valve 33 to an extent permitting a high rate of flow of oil through the loop 19. This causes the temperature of the oil to drop, because of its relatively quick passage through the tubes 16 and 16^a, when the expansible element 35 will be contracted by the drop of temperature of the oil passing it which permits the opening in the valve 33 to be reduced or closed. This retards the flow of oil through the tubes and causes a subsequent rise of temperature of the oil at the burner. Thus a uniform temperature of the oil at the burner is achieved automatically.

Normally, the by-pass valve 27 in the oil supply pipe 15 is closed. Should, however, it be found expedient to remove the tubes 16 and 16^a for replacement or repairs, the cut-out valves 21 and 21^a are closed and the by-pass valve 27 opened. The oil is then bypassed through pipe 25, while the tubes may easily be withdrawn from the chamber 41 by uncoupling union connections 20 and 20^a. Similarly, by-pass valve 39 in the return line 32 is normally closed, but should the thermostatic valve 33 not function properly, it can be kept closed by suitable weights or other means and the oil returned through pipe 38, and by-pass valve 39 may be manually adjusted to a required opening. The automatic stop and check valve is placed in the oil supply line as a safety feature. This valve closes instantly in case of a leak in the oil line at any point of the device, so that there is no danger of flooding the fire chamber with oil, even though the tubes should burn out.

The device can be very conveniently marketed by supplying it complete from union connection 28 to union connection 30, and valve 33 with by-pass 39 as assembled between Ts 36 and 36^a. In this manner it is suitable for application to any type of oil burning installation in which oil is conducted to a burner and surplus oil returned to a tank.

Various changes of form, proportion, minor details and combination of parts may be resorted to without departing from or sacrificing any of the advantages of the invention as defined in the appended claims.

Moreover, while I have referred in the speci-

fication and the claims to the heating apparatus as a furnace, it is to be distinctly understood that this term is to cover any form of heating equipment used in connection with boilers, also metallurgical furnaces, kilns or the like.

What I claim as new, is:

1. The method of heating oil supplied to the burner of an oil fired furnace which consists in subjecting the oil to the heat within the firebox of the furnace and automatically regulating the time the oil is subjected to the said heat to effect a uniform temperature at the burner. 75

2. The method of heating oil supplied to the burner of an oil fired furnace which consists in subjecting the oil to the heat within the firebox of the furnace and thermostatically regulating the time the oil is subjected to the said heat to effect a uniform temperature 85 at the burner. 85

3. In combination with an oil fired furnace having a burner, an oil supply pipe to the burner and an oil return pipe from the burner, a loop in the oil supply pipe projecting into the furnace and exposed to the heat therein, and thermostatic means to vary the rate of flow of oil through the said loop. 90

4. In combination with an oil fired furnace having a burner, an oil supply pipe to the burner and an oil return pipe from the burner, a loop in the oil supply pipe projecting into the furnace and exposed to the heat therein, a valve in the oil return pipe, and thermostatic means to open the valve when the temperature of the oil within the loop reaches a predetermined degree and to close the valve when the temperature drops below a predetermined degree. 95 100

5. In combination with an oil fired furnace having a burner, an oil supply pipe to the burner and an oil return pipe from the burner, a loop in the oil supply pipe projecting into the furnace and exposed to the heat therein, an expansible element in the oil supply pipe between the loop and the burner, and a valve in the oil return pipe, the said expansible element being operably connected to the said valve and being adapted to open the valve when expanded and to close the valve 110 115 when contracted.

6. In combination with an oil fired furnace having a burner, an oil supply pipe to the burner and an oil return pipe from the burner, a loop in the oil supply pipe projecting into the furnace, walls of refractory material surrounding the said loop defining a chamber having passages communicating with the fire box of the furnace, and thermostatic means to vary the rate of flow of oil through the said loop to effect a uniform temperature of oil at the burner. 120 125

In testimony whereof I have hereunto set my hand.

ALBERT W. MORSE.
